PHOTOTUBE CATHODE FORMATION

Hans W. G. Salinger, Fort Wayne, Ind., assignor,
by mesne assignments, to Farnsworth Research
Corporation, a corporation of Indiana

Application March 8, 1946, Serial No. 652,917

10 Claims. (Cl. 316—20)

1
This invention relates to the formation of photoelectric cathodes and particularly to the formation of such cathodes for maximum response to particular regions of the radiant energy spectrum.

Ordinary uses for phototubes require them to function in response to light which generally consists of a number of components of different wave lengths usually within the visible portion of the spectrum. The cathodes of such phototubes may be formed by conventional methods to give a satisfactory response to radiant energy of such a character. It is well known, however, that any phototube characteristically does not have the property of producing equal responses to radiant energy components of different wave lengths. It frequently is desirable to produce a phototube having a cathode which will give a maximum response to radiant energy of a particular wave length. For example, there are many uses for phototubes which are particularly responsive to infra-red light radiation.

It has been found, however, that it is difficult to form the cathode of such a phototube by conventional methods. One method, somewhat generally used heretofore, has been to carry the sensitizing of the cathode to a particular point and then to remove the phototube for testing. Such a method has the disadvantage that it is entirely a cut and try process and, because of variable factors involved in the sensitization of the cathode of such tubes, it is virtually impossible to produce two tubes having substantially the same response to the infra-red radiation. The cut and try method of sensitization has been made necessary by reason of the known fact that the response of a given phototube to light of different wave lengths differs. It, therefore, is not possible to employ the method of cathode formation used for ordinary light when it is desired to obtain a maximum response to infra-red light in particular, or in general to radiation of any particular wave lengths. The two responses may be considerably different.

It, therefore, is an object of the present invention to provide a method of and apparatus for forming a photoelectric cathode of a phototube to produce a maximum response to radiant energy of a predetermined wave length.

Another object of the invention is to provide a method of and apparatus for forming a photoelectric cathode for maximum response to radiant energy of a predetermined wave length by testing the response without interrupting the cathode formation process.

A further object of the invention is to provide a method of and apparatus for forming a photoelectric cathode for maximum response to radiant energy of a predetermined wave length without shielding the cathode from radiations of other wave lengths.

2
In accordance with the novel method of the invention, radiant energy of the desired wave length is projected onto the cathode. The intensity of the projected energy is modified intermittently. At the same time, sensitizing material is deposited on the cathode. The photoelectric output of the phototube representative of the radiation of predetermined wave length which is projected onto the cathode is impressed upon an indicating device, whereby to provide a continuous indication of the changing response of the cathode as the deposition of the sensitizing material is continued. By such a process the deposition of the sensitizing material may be arrested as soon as there is perceived an indication that the point of maximum or other predetermined response has been reached.

In accordance with a preferred embodiment of the apparatus for carrying out the novel method of the invention, there is provided a means including an episcotister for projecting intermittently upon the cathode of a phototube, radiant energy of the desired wave length. Means also are provided for depositing sensitizing material on the cathode. An output circuit for developing a signal effect representative of the photoelectric response by the cathode to the radiation of predetermined wave length is provided. In addition, there is provided an indicating device which is coupled to the output circuit, preferably through a filter for selecting a signal representative of the radiation of the predetermined wave length, whereby to enable the perception of the point of optimum sensitization of the cathode by means of which the desired response of the cathode to the radiation of predetermined wave length is obtained. Finally, facilities are provided for interrupting the cathode sensitization at any point when the maximum response of the cathode is indicated.

For a better understanding of the invention, together with other and further objects thereof, reference is made to the following description, taken in connection with the accompanying drawing, and its scope will be pointed out in the appended claims.

The single figure of the accompanying drawing is a diagrammatic representation of one form of apparatus for carrying out the novel method of cathode formation in accordance with the invention.

Having reference now to the drawing, there is shown a phototube having an envelope 1 within which there is mounted a cathode 2 and, adjacent to the cathode, an anode 3. It will be understood that these two electrodes are essential to the operation of any phototube. It, however, is contemplated to be within the scope of the present invention to have included in the envelope 1, other electrodes for cooperation with

the cathode and anode. For example, in addition to the cathode and anode, there may be mounted in the envelope one or more electron multiplying electrodes (not shown) having secondary electron emissive properties and any desired forms. The envelope 1 is provided with a tubulation 4 which is connected to an exhaust pump 5. This arrangement enables the evacuating of the main tube envelope which is necessary during the formation of the sensitized cathode surface and also for the completed tube. The main body of the envelope 1 preferably is enclosed within an oven (not shown) for heating to a temperature such as 200 degrees centigrade in accordance with well known practice.

Substantially any known process may be employed for depositing sensitizing material upon the cathode 2. As illustrated herein, the tubulation 4 contains a number of pellets such as 6 which may be of a caesium salt such as caesium chromate to which a suitable reducing agent is added whereby, upon the application of heat, metallic caesium is produced for deposition upon the cathode. In such a case, the portion of the tubulation 4 which contains the caesium chromate pellets is surrounded by a heating coil 7. This coil is connected through a switch 8 to a source of energy such as that represented by the battery 9.

It is contemplated that, in carrying out the process in accordance with this invention, other means for sensitizing the cathode may be employed. For example, the sensitizing material such as metallic caesium may be introduced into the phototube in small glass tubes which may be heated by means such as a gas torch so as to evaporate the caesium, in which state it is easily deposited on the cathode tube. Also, in some cases where increased sensitivity is desired, silver may be deposited over the caesium. All such processes for sensitizing the cathode are contemplated to come within the scope of this invention.

In accordance with one of the novel features of the present invention, there also are provided facilities for projecting radiant energy by a predetermined wave length upon the surface of the cathode 2 during the sensitization of this surface. Preferably this radiant energy is modified intermittently in intensity for a purpose to be described. One means for projecting such radiant energy onto the cathode surface comprises a source of light energy 11 which includes components of several different wave lengths. It will be assumed for the purpose of the present description that it is desired to produce a phototube having a cathode which has a maximum response to infra-red light. In such a case, the source 11 will be capable of producing radiant energy including energy at the wave length of the infra-red light.

The light emanating from the source 11 is projected by means of a lens system 12 into a beam whereby an image of the source is formed in a plane located between the source and the cathode 2. There is mounted in the image plane of the light source 11, apparatus for modifying the intensity of the beam. This apparatus comprises essentially an episcotister 13 such as a perforated disc which may be rotated by any suitable means (not shown). In the illustrated form of this apparatus, the disc is provided adjacent its periphery with a plurality of perforations such as 14. In such a case, the perforations are arranged so that they move in the

image plane of the light source 11 and successively coincide with the relatively small image point of the light source. By such means, the light beam is alternately transmitted through the perforations and interrupted by the opaque portions of the disc between the perforations.

It is contemplated to be within the scope of the invention that the episcotister employed may have any one of several other different forms. For example, instead of the perforations such as 14, the disc 13 may be provided with a plurality of serrations made in the peripheral edge thereof. Furthermore, the perforations, serrations, or whatever other form of structure is used may be entirely transparent whereby to transmit the light beam in full intensity or they may be semi-transparent or translucent, whereby to transmit the light beam in less than its maximum intensity. The only essential requirement of an episcotister for use in practicing this invention is that it be capable of intermittently modifying the intensity of the light beam.

The apparatus further includes a condensing lens system represented at 15 which is located between the episcotister 13 and the cathode 2. The function of the condensing lens is conventional; that is, to concentrate a relatively large portion of the light beam substantially uniformly over the surface of the cathode 2.

In the illustrated form of the apparatus embodying the invention, a filter element 16 capable of transmitting only the radiant energy of the predetermined wave length such as infra-red light, in the assumed case, is located between the condensing lens 15 and the cathode 2. In view of the foregoing description of the episcotister 13, it will be apparent that it is not necessary in all cases to provide a separate filter element 16 located as illustrated herein. It may be desirable to incorporate the filter element in the episcotister. One way of accomplishing this is to provide each one of the disc apertures such as 14 with individual filter elements having the desired wave length transmission properties. Other alternative arrangements of apparatus components will be suggested to those skilled in the art. It is contemplated, however, that all such apparatus organizations, whereby radiant energy of the desired wave length is projected upon the surface of the cathode being sensitized and is intermittently modified in intensity, come within the scope of the present invention. Where the tube envelope 1 is enclosed within an oven, a suitably located window is provided in the oven to enable the described projection of radiant energy upon the cathode 2.

The output circuit of the phototube includes a load impedance device such as a resistor 17 which together with a source of energy such as battery 18 is connected between the cathode 2 and the anode 3 of the phototube. The output circuit also includes a selective filter network 19 and an amplifier 21. The output circuit of the phototube may be entirely conventional. While the selective filter 19 is shown as a separate component, it may be incorporated in a conventional manner either with the load circuit resistor 17 or with the amplifier 19. The essential property of the filter network is to produce signal effects which are representative only of the intermittently modified radiant energy of the desired wave length which is projected upon the cathode 2 of the phototube. The essential requirement of the amplifier 21 is to suitably magnify the signal representative of the radiant energy of the de-

sired wave length so as to enable the use thereof in actuating an indicating device. In the case where the phototube includes, in addition to the cathode and anode, an electron multiplier, it may be that the signal effects derived from the tube and developed in the load circuit resistor 17 will be of sufficient magnitude to actuate the indicating device. In such a case the amplifier 21 may be omitted. It merely is necessary to select the signal effects representative of the radiant energy of the desired wave length from the signal effects representative of radiant energy of other wave lengths to which the cathode may be exposed.

The output circuit of the phototube, which may include the described filter and amplifier, is coupled to an indicating device which in the present instance is illustrated as a cathode ray oscilloscope 22. Specifically in accordance with the arrangement shown, the output circuit of the amplifier 21 may be coupled to the deflection elements of the oscilloscope by means of which the amplitude of the cathode ray deflection in one direction is controlled to produce traces on the oscilloscope screen representative of the phototube response to the radiant energy of the desired wave length.

In operating the described apparatus for carrying out the novel method of the invention, the light source 11 is energized and the episcotister 13 is rotated at a predetermined speed. It will be assumed for the purpose of the present description that the speed of rotation of the episcotister is such, in relation to the apertures 14 thereof, that the intensity of the light beam is modified approximately at the rate of one thousand times per second. In practicing the instant invention, the rate at which the intensity of the light beam is modified is more or less immaterial. Generally, however, unidirectional energy for use in measuring the response of the cathode is produced by a rectifying alternating current derived from a commercial source. Such alternating current energy usually is supplied at a frequency of 60 cycles per second. As is well known, regardless of the efficiency of filters used in conjunction with such rectifiers, it is not sufficiently high to eliminate all traces of the 60 cycle component from the signal effects produced in the output circuit of the phototube. Consequently, it is desirable to modify the intensity of the light beam at some frequency other than 60 cycles and all multiples thereof. It has been found that a rate of one thousand times per second for this purpose gives satisfactory results. Not only does it afford a means for distinguishing between the frequency of the primary power source and also from the cathode response to radiant energy of wave lengths different from the desired wave length, but also it affords a means for distinguishing the desired output from spurious signal effects which may be produced by other means such as thermionic electron emission by the cathode. In the assumed case, the infra-red light which is projected onto the cathode of the tube is modified in intensity one thousand times per second. The switch 8 is closed to energize the heating coil 7 whereby metallic caesium is reduced from the pellets 6. In a conventional manner the metallic caesium is condensed upon the surface of the cathode 2 which it is desired to sensitize.

As the sensitization of the cathode increases, the photoelectric response of the tube increases to develop signal effects in the load resistor 17. 75

In view of the fact that only the radiant energy of the desired wave length is modified before projection upon the cathode, in practicing this invention it is not necessary to use any special precautions for shielding the cathode from extraneous light of other wave lengths. Consequently, the photoelectric response by the cathode will be representative not only of the modified infra-red light, but also of all other light energy falling upon the cathode. Therefore, the signal effects which are produced in the load resistor 17 will represent all of the light energy to which the cathode is exposed.

However, only that portion of the signal effects derived from the output circuit of the phototube which represents the modified infra-red light will be developed in the output circuit of the selective circuit 19. These signal effects then are the only ones which are amplified by the amplifier 21 and are effective to actuate the cathode ray deflection of the oscilloscope 22. The manner and rate at which the cathode 2 becomes increasingly more responsive to the infra-red light thus is indicated by the increasing magnitude of the trace produced on the screen of the oscilloscope by the cathode ray.

When, by observation, the oscilloscope trace reaches a maximum, indicating that a maximum cathode response to infra-red light is reached, the switch 8 is opened to de-energize the heating coil 7 and thereby to interrupt the process of producing metallic caesium for deposition on the cathode. The cathode sensitization thus is terminated. In accordance with well known practice, in addition to de-energizing the heating coil 7, there may be included additional facilities for simultaneously cooling that portion of the tubulation 4 which contains the caesium chromate pellets 6. By such means the sensitization process may be terminated more quickly.

It may be seen that, by the employment of the method of phototube cathode sensitization described, phototubes may be produced so that all have substantially identical operating characteristics. Tube spoilage thus will be reduced materially over that of the present where cut and try methods of cathode formation are employed. Furthermore, by reason of variables encountered in the production of phototubes which are difficult or in many cases impossible to control, the maximum response of a number of phototubes produced by any process may vary considerably. The present process, however, may be employed to produce a plurality of phototubes all of which have identically the same response characteristics, even though in some cases individual tubes may be capable upon further sensitization of greater responses. It merely is necessary to fix quantitatively a desired output level for a number of phototubes and then to carry the cathode sensitization process only to the point where the desired output is produced. Furthermore, as previously suggested, the present process may be used advantageously where it is undesirable or inconvenient to take precautions against exposing the cathode to extraneous light during the cathode sensitization period.

It is contemplated to be within the scope of the present invention that it may be practiced in forming the cathodes of any electron discharge tubes which are required to have a predetermined response to radiant energy of substantially any predetermined wave length. Moreover cathodes of electron discharge tubes may be formed by the

present process and apparatus when such cathodes are required to have a maximum response to radiant energy covering in some cases a relatively wide range of wave lengths. Obviously, in such cases, it may be possible to eliminate the light filter and to merely modify the intensity of the radiant energy projected onto the cathode.

Furthermore, it may be desired to form the cathode of an electron discharge device which will have optimum response to more than one radiant energy component. For example, the present invention may be used advantageously to form a cathode which is to be responsive to radiant energy components of two different predetermined wave lengths. In such a case, two separate projecting systems both similar in character to the one disclosed herein may be employed. Each projecting system will be utilized to subject the cathode to one particular component of radiant energy having a predetermined wave length. In the case where it is desired to differentiate between the cathode response to the two different components, suitable apparatus may be employed to modify the intensity of the respective beams of radiant energy at two different rates. Selective filter networks corresponding to the rates of intensity modification will be included in the output circuit. The cathode sensitization may be effected in such a case so as to produce a desired balance in the response by the cathode to the different components of radiant energy. In view of the contemplated scope of the invention, it is to be understood that the references to the formation of a cathode for a phototube made in this specification and in the following claims merely is for the purpose disclosing a particular embodiment of the invention and such language accordingly is not intended to be construed as at all limiting in this respect.

Furthermore, it will be obvious to those skilled in the art that the invention may be practiced by the use of various forms of apparatus other than those disclosed specifically herein for illustrative purposes. For example, in practicing this invention, it is essential only to expose the cathode which is to be formed to radiant energy of the predetermined wave length, the intensity of which energy is modified intermittently so as to be distinguishable from radiant energy of other wave lengths to which the cathode may be exposed at the same time. For example, instead of using a source of white light such as the disclosed source 11, there may be employed a source of radiant energy having only one component which is that of the desired wave length. Also, as previously suggested, means other than those disclosed for modifying the intensity of the radiant energy may be used without departing from the invention.

While there has been described what, at present, is considered the preferred embodiment of the invention, it will be obvious to those skilled in the art that various changes and modifications may be made therein without departing from the invention, and, therefore, it is aimed in the appended claims to cover all such changes and modifications as fall within the true spirit and scope of the invention.

What is claimed is:

1. Apparatus for forming a cathode of an electron discharge tube for predetermined response to radiant energy of a predetermined wave length comprising, a cathode to be sensitized, means for directing a beam of radiant energy of said predetermined wave length onto said cathode, means

for periodically modifying the intensity of said beam, means coupled to said cathode to register the response by said cathode to said periodically modified radiant energy of predetermined wave length, and means for concurrently depositing sensitizing material upon said cathode.

2. Apparatus for forming a cathode of an electron discharge tube for predetermined response to radiant energy of a predetermined wave length comprising, a tube envelope, a cathode to be sensitized in said envelope, means for developing a beam of radiant energy of said predetermined wave length, means for directing said beam of said radiant energy onto said cathode, means located in the path of said beam for intermittently modifying the intensity of said beam, means coupled to said cathode for developing a voltage representative of the response by said cathode to the radiant energy of predetermined wave length received thereby, means coupled to said voltage developing means to register the response by said cathode to said radiant energy of predetermined wave length, and means for depositing sensitizing material upon said cathode until the predetermined response by said cathode to said radiant energy of predetermined wave length is registered by said registering means.

3. Apparatus for forming a cathode of an electron discharge tube for maximum response to radiant energy of a predetermined wave length comprising, a tube envelope, a cathode to be sensitized in said envelope, a source of radiant energy of said predetermined wave length, means for directing a beam of said radiant energy onto said cathode, means including an episcotister located in the path of said beam for intermittently modifying the intensity of said beam, means including an output circuit connected to said cathode for developing a voltage representative of the response by said cathode to the radiant energy of predetermined wave length received thereby, means including an indicator coupled to said output circuit to register the response by said cathode to said radiant energy of predetermined wave length, and means for depositing sensitizing material upon said cathode until the maximum indication by said indicator is registered.

4. Apparatus for forming a photoelectric cathode of a phototube for maximum response to infra-red radiation comprising, a tube envelope, a cathode to be photosensitized in said envelope, a source of light, means including an optical system for forming said light into a beam and for projecting said beam onto said cathode, an episcotister located in the path of said beam for periodically interrupting said light beam, an infra-red filter element located in front of said cathode, an output circuit for said phototube connected to said cathode for developing a signal voltage representative of the photoelectric response by said cathode to the interrupted infra-red radiations received thereby, means connected to said phototube output circuit for developing amplified signal voltages representative of the infra-red output of said phototube, an indicating device, means including a filter network for impressing upon said indicating device said amplified signal voltages representative of the interrupted infra-red radiation projected onto said cathode, and means for evaporating photo-sensitizing material upon said cathode until the maximum indication by said indicating device is produced.

5. Apparatus for forming a photoelectric cathode of a phototube for maximum response to infra-red radiation comprising, a tube envelope,

a cathode to be photosensitized and an anode in said envelope, a tubulation extending from said envelope and including caesium sensitizing material, means for connecting said tubulation to an exhausting pump for evacuating said envelope, a source of light, an optical system for forming said light into a beam, a rotating disc having a plurality of apertures located in the path of said light beam for interrupting said light beam at a predetermined frequency, an infra-red filter element located in said beam in front of said cathode, means for projecting said interrupted light beam through said filter and onto said cathode, an output circuit for said phototube connected between said cathode and said anode for developing a voltage representative of the total photoelectric response by said cathode to the light radiations received thereby, a filter network coupled to said phototube output circuit for selecting only the signal voltages representative of the interrupted infra-red radiation projected onto said cathode, an amplifier having an input circuit connected to said filter network and an output circuit for developing amplified signal voltages representative of the output of said phototube, an indicating device connected to said amplifier output circuit for control thereby to produce visible indications of the infra-red response of said phototube cathode, and means for heating that portion of said tubulation including the caesium sensitizing material for effecting evaporation of said caesium until the maximum indication of infra-red response is produced on said indicating device.

6. Apparatus for forming a photoelectric cathode of a phototube for maximum response to infra-red radiation comprising, a tube envelope, a cathode to be photosensitized and an anode in said envelope, a tubulation extending from said envelope and including a plurality of caesium chromate pellets, means for connecting said tubulation to an exhausting pump for evacuating said envelope, a source of white light, an optical system for forming said light into a beam whereby to create an image of said light source in a predetermined plane, a rotating disc having a plurality of apertures located in said predetermined plane for interrupting said light beam at a predetermined audible frequency, an infra-red filter element located outside of said tube envelope in front of said cathode, means for projecting said interrupted light beam through said filter and onto said cathode, a load circuit connected between said cathode and said anode for developing a voltage representative of the total photoelectric response by said cathode to the light radiations received thereby, a filter network connected to said phototube load circuit and having parameters for selecting only the signal voltages representative of the interrupted infra-red radiation projected into said cathode, an amplifier having an input circuit connected to said filter network and an output circuit for developing amplified signal voltages representative of the output of said phototube, an oscilloscope connected to said amplifier output circuit for control thereby to produce visible indications of the infra-red response of said phototube cathode, and means including a heating coil surrounding that portion of said tubulation including the caesium chromate pellets for effecting evaporation of said pellets until the maximum indication of infra-red response is produced on said oscilloscope screen.

7. The method of forming a photoelectric cathode for predetermined response to radiant energy of a predetermined wave length comprising

the steps of, projecting onto the cathode to be formed a beam of radiant energy of said predetermined wave length having an intensity which is periodically modified, depositing sensitizing material on said cathode, amplifying the photoelectric output of said cathode representative of its response to said radiant energy of predetermined wave length, and obtaining an indication of said amplified photoelectric output.

- 10 8. The method of forming a photoelectric cathode for predetermined response to radiant energy of a predetermined wave length comprising the steps of, developing a beam of interrupted radiant energy of said predetermined wave length, projecting said interrupted radiant energy onto the cathode to be formed, concurrently depositing caesium on said cathode, amplifying the photoelectric output of said cathode derived from its response to said interrupted radiant energy of predetermined wave length, impressing said amplified output upon an indicating device, and arresting said deposition of caesium when a predetermined indication is observed on said indicating device.
- 25 9. The method of forming a photoelectric cathode for maximum response to infra-red radiant energy comprising the steps of, developing a beam of light including an infra-red radiant energy component, interrupting said beam at a predetermined frequency, filtering said interrupted beam to obtain only the infra-red component thereof, projecting said infra-red interrupted radiant energy onto the cathode to be formed, concurrently evaporating sensitizing material for deposition on said cathode, selecting from the total photoelectric output of said cathode including that derived from its response to said interrupted infra-red radiant energy only the output of said cathode derived from said infra-red radiant energy, amplifying said infra-red output, impressing said amplified infra-red output upon an indicating device, and arresting said evaporation when a maximum indication is observed on said indicating device.
